United States Patent Office

Des. 181,410
Patented Nov. 12, 1957

181,410

COMBINED PERFUME BOTTLE AND HOLDER OR SIMILAR ARTICLE

Eric de Kolb, New York, N. Y., assignor to Coty, Inc.,
New York, N. Y., a corporation of Delaware

Application March 4, 1957, Serial No. 45,052

Term of patent 14 years

(Cl. D86—10)

Fig. 1.

Fig. 2.

Fig. 3.

Fig. 4.

Fig. 1 is a top plan view of a combined perfume bottle and holder or similar article, showing my new design; Figure 2 is a side view thereof in elevation; Figure 3 is a bottom end view in elevation; and Figure 4 is a top end view in elevation.

I claim:

The ornamental design a combined perfume bottle and holder or similar article, substantially as shown.
